UNITED STATES PATENT OFFICE.

HUBERT ZINS, OF WABASSO, MINNESOTA.

VETERINARY OBSTETRICAL FORCEPS.

Application filed November 3, 1927. Serial No. 230,813.

This invention relates to an obstetrical forceps adapted to be used for the purpose of delivering a pig presented with its posterior end first and when one or both of its feet may be felt, and has for one of its objects to provide a novel, simple and highly efficient instrument of this character which shall be so constructed as to permit it to be readily inserted into the vagina and engaged with a leg of the pig.

With the foregoing and other objects in view, the nature of which will appear as the description proceeds, the invention consists in the construction, combination and arrangement of parts hereinafter fully described and claimed, and illustrated in the accompanying drawing, wherein.

Figure 1 is a top plan view of the forceps,

Figure 2 is a view in side elevation of the forceps, and

Figure 3 is a transverse sectional view taken on the plane indicated by the line 3—3 of Figure 1.

The forceps comprise an elongated body 1, a handle 2 located at the rear end of the body and of triangular contour, and a gripping loop 3 located at the front end of the body. The body 1 has an upwardly and forwardly inclined front end portion, and it is made up from two tubular members 4 and an intervening member or web 5. The tubes 4 and web 5 may be welded or secured together in any other suitable manner. The handle 2 is tubular and is formed integrally with the rear ends of the tubes 4, and these parts are preferably formed from a single length of metal tubing. The handle 2 is strengthened and reenforced by a triangular rod 6 which is arranged therein and of which the front ends terminate short of the corresponding ends of the side members of the handle. Said members of the handle 2 are provided at points forwardly beyond the reenforcing rod 6 with openings 7. The loop 3 is formed from resilient wire, and its extended or side portions 8 are slidably arranged within the tubes 4. The rear ends of the loop members 8 extend through the openings 7 and are connected to a pull ring 9 arranged within the handle 2.

In practice, the forceps are inserted into the vagina of the brood sow with the loop 3 surrounding the forefinger of the left hand

and with the finger extending along and beyond the inclined front end of the body 1. The loop 3 is now engaged with a foot of the pig, and thereafter the loop is closed about the foot by exerting a rearward pull on the ring 9. The pig is now ready for final delivery, and this is accomplished by exerting a rearward pull on the forceps while maintaining the loop 3 closed about the leg of the pig.

The upwardly and forwardly inclined front end of the body 1 permits the body and loop 3 to be brought into direct line with the finger that is to carry the loop forward, and this is accomplished by bringing the front end of the body to the finger tip.

As the handle 2 and tubes 4 are made from a single length of tubing, as the handle is reenforced by the rod 6, and as the tubes are connected together by the intervening web 5, the forceps is strong and durable and furthermore it may be manufactured and sold at a comparatively low cost. The forceps are also adapted, as will be apparent, to be used for the purpose of delivering the fetus of dogs, cats and other small animals.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. A forceps comprising a body having an upwardly and forwardly inclined front end portion and provided with parallel passages, a handle secured to the rear end of the body, and a gripping loop having extended side members passing through the passages and connected at their rear ends.

2. A forceps comprising a body consisting of parallel tubes connected together, a looped tubular handle having its ends connected to the rear ends of the tubes and having its side members provided with openings communicating with the tubes, a gripping loop having extended side members passing through the passages and openings and connected at their rear ends, and a reenforcing rod within the handle.

3. A forceps comprising a body consisting

of parallel tubes and an intervening web, a looped tubular handle having its ends connected to the rear ends of the tubes and having its side members provided with inner

5 openings communicating with the tubes, a reinforcing rod arranged within the handle, a gripping loop having extended side mem-

bers passing through the tubes and openings, and a pull member connected to the rear ends of the side members of the gripping 10 loop.

In testimony whereof I affix my signature.

HUBERT ZINS.
